[57] **CLAIM**

The ornamental design for a combination rolled coloring scroll, rolled wall-mounting adhesive, and dispenser therefor, as shown and described.

DESCRIPTION

FIG. 1 is a top, front, and left side perspective view of a combination rolled coloring scroll, rolled wall-mounting adhesive and dispenser therefor showing my new design;

FIG. 2 is a left side elevational view thereof, the right side being a mirror image of that shown;

FIG. 3 is a reduced top plan view thereof;

FIG. 4 is a reduced front elevational view thereof;

FIG. 5 is a reduced bottom plan view thereof;

FIG. 6 is a reduced rear elevational view thereof; and,

FIG. 7 is a vertical cross-sectional view thereof, taken along line 7—7 of FIG. 1.
